COKE OVEN CHARGING MACHINE

Carl Still, Recklinghausen, Germany

Application June 18, 1930, Serial No. 462,015,
and in Germany June 20, 1929

5 Claims. (Cl. 214—18)

The usual constructions of machines for charging horizontal coke ovens with rammed coal cakes have the defect and disadvantage that a certain free space is left between the oven door opening and the end of the ramming box facing the ovens, which space is required on the one hand for permitting the machine to travel along the front of the oven battery outside of the vertical buckstays and on the other hand for giving sufficient 5 passageway to the operators. The consequence of this arrangement, however, is that the coal cake is not guided through the entire length of its sides when being passed from the ram box to the oven chamber, causing thereby the risk of 10 its being damaged or broken especially when its height exceeds about $2\frac{1}{2}$ to 3 meters and more particularly with narrow coke ovens which are 15 more and more adopted in recent times.

The coke oven charging machine forming the 20 subject of my invention aims at establishing an uninterrupted side guiding of the coal cake from the ram box to the oven chamber in order to secure its introduction into the oven in undamaged condition.

25 According to the invention, this is effected by displacing the ram box or at least its two side walls, after ramming, on the lower carriage of the machine in the direction of the oven axis in such a way that the ends of the walls of the ramming 30 chamber are brought close to the door frame of the oven.

An embodiment of the invention is shown in the accompanying drawings wherein

Fig. 1 represents a vertical section on the line 35 I—I of Fig. 2 through the machine parallel to the front of and looking towards the ovens.

Fig. 2 is a vertical longitudinal section on the line II—II of Fig. 1 through the centre of the ramming box, and

Fig. 3 is a horizontal section, mainly of the ramming box, on the line III—III of Fig. 2. The manner of representation used in Fig. 3 differs from that of Fig. 2 in that the ramming chamber is shown in the above-mentioned displaced 45 position.

Figs. 4, 5 and 6 are detailed views of the end of the charging device nearest the oven, illustrating the successive steps during which the cake within the oven is further compressed.

The lower part of the machine is in the usual 50 manner formed by an under carriage 1 which can be run on the track 2 along the front of the ovens.

In the example illustrated, it is assumed that 55 the machine, as shown in Fig. 1, is combined with

a coke pushing device 3, with which, however, the invention is not concerned. The coal hopper 4 is rigidly connected with the carriage 1. The ramming box 5 is arranged below the discharge end of the hopper. The two side walls 6 of the box 5 are connected with an iron framework 8 by means of intermediate devices 7, which allow the said walls 6 to be drawn apart through a small distance after the ramming has been completed. The framework 8 is displaceable through a certain distance on the under carriage 1 of the machine in the direction of the axis of the oven by rollers 9 which run on rails 10. Racks and gear wheels 11, 12 serving for displacing the frame are operated by a motor 13, secured to the carriage 1, 60 through other self-locking gearing 14, 15.

The framing 8 serves also to support the bottom plate 16 of the ramming box and a pair of sprocket wheels 17 with a Gali chain 18 running on the wheels. The chain 18 is coupled at 19 75 with the bottom plate 16 of the ramming box. The sprocket wheels 17 can be driven, through intermediate gearing (not shown), by another motor 25, supported on the carriage 1. The base 16 carries, at its front and rear ends, shields 20 80 and 21 which engage with and support the rammed cake at the front and back. The rams are indicated in Fig. 1 at 24, the machinery for operating them being omitted. The shields 20 and 21 are removably attached to the bottom plate 16 by means of pins or other well-known suitable means and are carried thereby during its forward movement. The shield 21 is further supported by plate 30 which is rigidly fixed to bottom plate 16. 85

90 The machine is operated in the following manner:—

The ramming box 5 is normally, i. e. for the travel along the track 2 and during the ramming operation in the position relatively to the 95 ovens as shown in Fig. 2 where a certain free space exists between the forward end 26 of the box walls 6 and the door frame 27 which space is partially occupied by the buckstays 28. For undertaking a new ramming, the two side walls 100 6 are placed at the normal distance corresponding to the width of the rammed cake and the two shields 20 and 21 are also in position. Then the box 5 is filled with coal in the usual manner from the hopper 4 which is rammed so that a compressed cake 23 (Fig. 2) is produced. The whole machine may, during this time, occupy 105 at any position desired along the whole oven battery. The machine is now brought in front of the oven chamber 22 (Fig. 3) to be charged, 110

from which both doors have been removed, so that the box 5 is exactly opposite the oven chamber.

After the machine has been so positioned the two walls 6 of the ramming box are slightly drawn apart from one another by the apparatus 7, in order to provide some lateral play for the coal cake 23 during its later movement into the oven chamber, and then the framing 8 carrying the box 5 is displaced in the direction of the axis of the oven on the rails 10 by the motor 13 and by gear 11, 12, 14, 15 until the box occupies the position shown in Fig. 3 in which its front end 26 lies close against the door frame 27 of the oven chamber 22. The sprocket wheels 17, actuated by the motor 25, then move the bottom plate 16 of the box 5, connected by the chain 18 with the said wheels, forward into the oven chamber 22. Since the walls 6 of the box 5, which has now been moved up to the oven chamber, provide continuous and steady side guides for the cake 23, the latter is introduced into the chamber 22 smoothly and in undamaged condition. One of the advantages gained by moving the framing 8 in the direction of the oven is that the means supporting the forward end of the bottom plate 16 of the box 5 are brought closer to the oven sole, thus avoiding any bending of the free front end of the plate 16 between the machine and the oven.

The efficient guiding of the coal cake obtained in this way obviates any chance of its being broken up, even if the cake is of a considerable height and somewhat narrow. This result is assisted by the provision of the two shields 20 and 21 which prevent portions of coal from being broken off at the both ends of the cake during its insertion.

After the coal cake has been completely introduced into the chamber 22, the shield 20 supporting its front end is removed from the side of the oven which is situated opposite to the machine and replaced by the respective oven door. The shield 21 at the opposite end is coupled in this position with the two side walls 6 of the box 5 and simultaneously detached from the bottom plate 16. The plate 16 is now withdrawn from the oven chamber 22 by the chain 18. By the shield 21 which is fixed to the side walls 6 the cake 23 is prevented from being withdrawn together with the bottom plate 16 and remains, therefore, in the oven chamber 22. The shield 21 is then released from the walls 6 of the box 5 and is drawn back, by a suitable winding device, into its original position, as shown in Figs. 2 and 3. Finally, the walls 6 are also brought back to their normal position, shown in Fig. 2, by the rearward movement of the framing 8 fixed to them on the carriage 1. The whole machine can now be moved away from the charged oven and the door inserted on this side and the oven chamber 22 consequently closed.

The constructional arrangements for moving the ramming box in the direction of the axis of the oven, which movement is a characteristic feature of the invention, can be modified. For example, the object of the invention would also be obtained if the two side walls 6 of the ramming box soon after they had been drawn apart, or during and in conjunction with this procedure, alone were moved in the direction of the axis of the oven up to the oven chamber.

Also, in this case the framing parts 8, serving as the side supports of the walls 6 of the ramming box, might be moved with the walls. In this mod-

ification the bottom plate of the ramming box will be directly supported on the lower carriage 1 and its chain drive will be rigidly connected with the latter.

A useful modification of the coke oven charging machine as described above can be provided, without making important changes in the whole construction, by the following arrangement whereby, after the ramming box has been moved in the direction of the axis of the ovens for the guiding purpose aforesaid, the rear end of the coal cake introduced into the oven chamber can be compressed and consolidated.

In this modification, the cake 23 is formed with the machine shown in Fig. 2 and the movement of the whole machine along the oven battery up to the oven chamber 22 to be charged is accomplished exactly as described above. The particular feature of the modification consists in the movement of the ram box walls which follows the ramming operation only to such an extent that thereafter a further movement of about 2 to 3 inches is still available before the ram box walls abut the frame of the oven door.

This usually requires that, in the displaced position of the ramming chamber 5 (see Fig. 3), a small space should be left between the front edges 26 (which are shown by a dotted line in Fig. 3) of the two ram box walls 6 and the door frame 27 of the oven chamber 22. This space does not interfere with the safe introduction of the coal cake from the ramming box 5 into the oven chamber 22. It is also possible that this space need not at all be provided or may be reduced to a very small amount, if the door frame 27 of the oven chamber is so proportioned and constructed that the front ends of the walls 6 can be inserted in it for a slight distance.

After the rammed cake 23 has been completely introduced in the oven chamber 22, the rear shield 21 is released from the bottom plate 16 and connected with the two side walls 6 of the ramming chamber by means of the bars 29 which are inserted through slots in the side walls 6 and which then support the back side of shield 21. The whole ramming box 5 is now moved towards the oven chamber 22 through the short open space still remaining. Thereby the rear shield 21, moving with the walls 6 of the ramming box, causes the adjoining rear portion of the cake to be compressed and consolidated. After this has been effected, the bottom plate 16 of the ramming box is again withdrawn from the oven chamber 22 by the chain 18, as described above the rear shield 21 supporting and retaining the rammed cake 23, so that it remains in the oven chamber 22. This operation, as briefly described, will be made clear and more readily understood by referring to Figs. 4, 5 and 6 of the drawings. Fig. 4 shows the position of shield 21 and plate 30 when the coal cake has just been pushed into the oven. Fig. 5 shows the connection between shield 21 and the side walls 6. By the introduction of the bars 29 through slots in the side walls 6, the U-shaped plate 30 serving as a positioning device 140 under normal operations, is drawn back together with the bottom plate 16 to which it is rigidly attached, and under these conditions the shield 21, which is not connected with the bottom plate 16, remains in its position as illustrated in Fig. 4. Fig. 6 shows how the side walls 6 are moved forward against the front of the oven 22, and due to the connections 29 the shield 21 is also moved forward for compressing the coal cake 23 within the oven chamber. After this operation the bot-

tom plate 16 is withdrawn and the shield 21 is removed as above described.

The arrangement representing the essential feature of the invention, in which the rammed coal cake is guided from the ramming box to the oven chamber by this ramming box being moved in the direction of the axis of the oven up to the oven door frame, has the advantage of great simplicity and stability and at the same time avoids all manual manipulations. More particularly all manual operations in the immediate neighbourhood of the door frames of the oven chamber are obviated, which operations, because of the lack of sufficient free space between the buckstays and because of the heat radiated from the oven chamber, make this work exceedingly difficult. As a result of this arrangement the ovens can be operated more easily and expeditiously, which is of great importance particularly with modern ovens with their greatly increased outputs and short carbonizing periods. All the above-named advantages also increase the reliability of the operation.

What I claim is:—

- 25 1. In a coke oven charging machine of the ramming type, a carriage travelling along the oven battery, a framing supported by said carriage, a ramming box carried by said framing, and means for moving the framing with the ramming box carried thereby in the direction of the oven axis and to such an extent that the front end of said box substantially adjoins the oven.
- 30 2. In a coke oven charging machine of the ramming type, a ramming box having movable side walls, and means for moving said walls in the direction of the oven axis to such an extent that the front ends of said walls substantially adjoin the oven and form a continuous guiding means for the coal cake during its insertion into the oven chamber.

3. In a coke oven charging machine of the ramming type, a ramming box, and means whereby said ramming box with the coal cake contained therein, is displaced in the direction of the oven axis to such an extent that the front end of said box lies closely adjacent the oven and forms a continuous guiding means for the coal cake during its complete insertion into the oven chamber.

4. In a coke oven charging machine of the ramming type, a ramming box having side walls and end shields, means whereby the side walls of the ramming box, after the coal cake has been rammed, are displaced in the direction of the oven axis to such an extent that the front ends of said side walls substantially adjoin the oven and form a continuous guiding means for the coal cake during its complete insertion into the oven chamber, in combination with means whereby further displacement of the rear end shield effects compression of the rear end of the coal cake within the oven chamber.

5. In a coke oven charging machine of the ramming type, a ramming box having side walls, end shields and a bottom plate, means whereby the side walls of the ramming box, after the coal cake has been rammed, are displaced in the direction of the oven axis to such an extent that the front ends of said side walls substantially adjoin the oven and form a continuous guiding means for the coal cake during its complete insertion into the oven chamber, means for moving the bottom plate of the ramming box with the coal cake thereon into the oven chamber, means for moving the rear end shield of the ramming box against the coal cake to effect compression of the rear end thereof within the oven chamber, and means for withdrawing said bottom plate while said end shield is in position against the end of said coal cake.
